CLAIM

The ornamental design for a container, as shown.

DESCRIPTION

FIG. 1 is a perspective view of a container showing our new design;

FIG. 2 is a side elevational view of one side of the FIG. 1 design, the lid and the handle being shown in phantom; FIG. 3 is a side elevational view of the opposite side of the FIG. 1 design, the lid and the handle being shown in phantom;

FIG. 4 is a top plan view of the FIG. 1 design, the handle being shown in phantom;

FIG. 5 is a bottom plan view of the FIG. 1 design, the handle being shown in phantom;

FIG. 6 is a back end elevational view of the FIG. 1 design, the lid being shown in phantom; and,

FIG. 7 is a front end elevational view of the FIG. 1 design, the lid and the handle being shown in phantom.

The broken lines in the drawings are for illustrative purposes only and form no part of the claimed design.

1 Gram, 2 Drawing Sheets
